UNITED STATES PATENT OFFICE.

JOHN F. BERGH, OF HAWARDEN, IOWA.

DOOR AND HINGE CONSTRUCTION FOR HAY DOORS.

Application filed May 5, 1924. Serial No. 711,060.

To all whom it may concern:

Be it known that I, JOHN F. BERGH, a citizen of the United States, and a resident of Hawarden, in the county of Sioux and 5 State of Iowa, have invented certain new and useful Improvements in Door and Hinge Constructions for Hay Doors, of which the following is a specification.

My invention relates to barn door constructions and is adaptable particularly to 10 the doors of a hay loft.

It is my object to provide a door and hinge construction wherein the doors may extend to the roof of a barn and when 15 opened outwardly will assume such a position that their opening will not be interfered with by the projecting gable ends.

Another object is to provide such a door and hinge construction which is of simple, 20 durable and substantial construction.

A further object is to provide such a construction wherein the doors may be readily opened and locked in open position from the inside of the hay loft without it being 25 necessary for the person opening the door to reach out any considerable distance.

Another object is to provide a hinge adaptable to be used with such a door construction, and which, when folded for shipment, will occupy a minimum amount of 30 space.

With these and other objects in view, my invention consists in the construction, arrangement and combination of the various 35 parts of my device, whereby the objects contemplated are attained, as hereinafter more fully set forth, pointed out in my claims, and illustrated in the accompanying drawings, in which:

40 Fig. 1 is a front elevation of a portion of a barn with my invention embodied therein.

Fig. 2 is a vertical sectional view taken on the line 2—2 of Fig. 1, one of the doors being shown partially opened.

45 Fig. 3 is a horizontal sectional view taken on the line 3—3 of Fig. 1.

Fig. 4 is a perspective view of a hinge in closed position, and

50 Fig. 5 is a perspective view of a hinge in open position, the braces being folded inwardly.

In the ordinary hay loft it is desirable to extend the doors entirely to the roof in order that the hay may be packed to the highest possible level, and in order that a carriage and rail may be utilized in raising

the hay, which is preferably positioned just under the peak of the roof.

In Fig. 1 I have shown a barn in which the doors are so constructed, the front of the 60 barn being shown at 10, the projecting gable ends of the roof at 11 and the carriage rail at 12.

It will be noted that were the doors, 13, hinged with the ordinary type of hinge that 65 it would be impossible to swing them outwardly very far before the inclined edge of the doors would contact with the gable, 11. In order to obviate this difficulty, doors have been constructed so low that they may 70 be swung entirely around on their hinges without entering the plane of the roof.

Another method for solving the problem has been to form the doors in four sections, 75 the triangular portions above being severed from the rest of the doors and hinged so as to fold downwardly.

It will be seen that the first construction is undesirable because the door should preferably be extended to the roof in order to 80 obtain the advantages already mentioned.

The second construction involves the use of four piece doors and necessitates more time and labor in closing the doors.

A further method of solving the difficulty, 85 and one which has been extensively used, is the hinging of the doors at the bottom so as to swing downwardly. The objectionable feature of this construction lies in the weight of the doors, it being necessary in 90 most instances to employ a team and a block and tackle to raise the doors to closed position.

My invention is designed to eliminate all 95 of these objections and to provide a structure in which the doors may be opened without the employment of a great amount of force. I have found in the use of a full size pair of doors constructed in accordance with my invention that a small child may 100 readily open and close the doors.

My improved hinge construction includes the members, A and B, each of which comprises an arm, 14, adapted to be bolted to the door, or the side of a barn, as the case 105 may be, and an outwardly extending arm, 15, having at its end the ordinary loops, 16, which form the hinge joint. The two members of the hinge are connected by a pintle, 17. Brace members, 18, are pivoted, or 110 otherwise suitably secured to the arms, 15, and extend diagonally to the arms, 14,

where the openings, 19, are provided, registering with the openings, 20, in the arms, 14, for receiving a bolt which serves to secure the braces to the arms, 14, and to secure the entire hinge to the door or side of the barn. Openings, 21 and 22 in the outer and inner ends, respectively, of the arms, 14, are provided for receiving bolts.

In order to support the weight of the door it is necessary to provide the braces, which I will now describe. The member, A, has the brace, 23, secured to the outer end of the arm, 15, by the same rivet, 24, which secures the brace, 18. The brace, 23, extends upwardly at an angle and has the opening, 25, to receive a bolt. The brace, 26, is secured to the arm, 15, of the member, B, in the same manner as the brace, 23, is secured to the member, A, and extends downwardly at an angle. When the hinge is installed, the member, A, is bolted to the side of the barn by means of bolts, 27, and the member, B, is likewise secured to the door. The brace, 23, is secured to the side of the barn, and the brace, 26, is secured to the door.

It will be seen that the weight of the door will be transmitted diagonally upward through the braces, 26 and 23, respectively, to the side of the barn regardless of the position of the door.

I provide the hooks, 28, which are pivoted to the screw eyes, 29, and normally supported by the screw eyes, 30, in inoperative position. The door is secured in closed position by means of the small hooks, 31, fixed to the floor, 32, of the barn and which are designed to be hooked into the screw eyes 33, on the door. The upper end of the doors may be secured in closed position by the spring locking bolts, 34, which may be of ordinary construction.

When it is desired to open the doors, the latches, 34 and 31, are released and the doors swung outwardly until they have assumed the position shown in Fig. 2. The hook, 28, may then be released from its retaining eye, 30, and grasped as shown in Fig. 2 for swinging the doors to their complete open position, as shown in Fig. 3 at the left hand side of the figure. The hook, 28, may then be hooked into the eye, 35, secured to the side of the barn in order to hold the doors in open position.

It will be noted that the hooks, 28, are so positioned that they are readily accessible from the door opening without necessitating the arm of a person being extended very far. The hinge pivots are so positioned that when the door has been opened it will lie in a plane outside of the gable of the roof. The separating of the door from the side of the barn as it swings outwardly allows access to the hook, 28, in order to complete the movement of the door to open

position and to lock it in such position. By positioning the hooks, 28, on the outside of the door they are brought to the correct position when the door is swung around on its hinges.

The hinges are designed to occupy the least amount of space when being shipped, and for this purpose the braces, 23 and 26, are pivoted so as to swing to the position shown in Fig. 5, in which position the hinge members all lie in the same plane.

The hinge is constructed in the cheapest possible manner with a view at the same time of obtaining the maximum strength when it is installed, and in this connection, the braces, 18, are not riveted to the members, 14, but are adapted to be secured thereto by the same bolt which holds the hinge to the door, or the side of the barn, as the case may be.

It will be seen that my improved hinge construction is designed to bear the weight of a heavy door and to eliminate the disadvantages of doors constructed as explained heretofore.

It is obvious that a door constructed in accordance with my invention may be readily swung to open position with the least amount of trouble, and as readily swung back to closed position.

Some changes may be made in the construction and arrangement of the parts of my invention without departing from the real spirit and purpose of my invention, and it is my intention to cover by my claims any modified forms of structure or use of mechanical equivalents which may be reasonably included within their scope.

I claim as my invention:

1. A hinge for barn doors comprising two L-shaped members of strap metal, each having a main and lateral arm, the lateral arms being hinged together at their ends, braces connecting the main and lateral arms of each L-shaped member and secured to the lateral arms near the hinge pivots by means of rivets, and second braces secured to the lateral arms by means of the said rivets, said second braces being movable to positions extending diagonally relative to the lateral arms to the planes of the main arms, and being foldable to positions in alignment with the lateral arms.

2. A hinge for barn doors comprising two L-shaped members of strap metal, each comprising a main and lateral arm, the ends of the lateral arms being provided with hinge loops rolled in a direction away from the main arms, the hinge loops registering and being pinned together to form a hinge joint such that when the hinge is in closed position, the lateral arms will be positioned adjacent each other with a space substantially equal to the diameter of the hinge pin between them, braces extending diagonally

nally from the main arms to the lateral arms and secured thereto near the hinge axis by rivets, and movable braces secured to the lateral arms by, means of said rivets, occupying the space between the lateral arms when in closed position, said movable braces being movable to position in alignment with the lateral arms or to position inclined away therefrom.

10. 3. A hinge for barn doors comprising two members adapted to lie in the same plane when the hinge is closed, each of said members having laterally-extending arms hinged together at their ends, braces extending between the laterally-extending arms near the hinge axis and those portions of the hinge which lie in the same plane when the hinge is in closed position, and braces extending from the respective laterally-projecting 15 arms of the hinge members diagonally upward and diagonally downward respectively 20

to the first mentioned plane of the hinge members, said last mentioned braces being pivoted and movable to a position in alignment with the laterally-projecting arms. 25

4. A hinge for barn doors comprising two members adapted to lie in the same plane when the hinge is closed, each of said members having laterally-extending arms hinged together at their ends, and braces extending from the respective laterally-projecting arms of the hinge members diagonally upward and diagonally downward respectively to the first mentioned plane of the hinge members, said braces being pivoted and movable to a position in alignment with the laterally-projecting arms. 30 35

Signed at Hawarden, in the county of Sioux, and State of Iowa, this 28th day of April, 1924.

JOHN F. BERGH.
